MOBILE ACCOUNTING DEVICE

Arthur K. Watson, New Canaan, Conn., William L. Lewis, Binghamton, N. Y., and James L. Walsh, Washington, D. C., assignors to International Business Machines Corporation, New York, N. Y., a corporation of New York

Original application July 10, 1942, Serial No. 450,470. Divided and this application January 9, 1945, Serial No. 572,066

3 Claims. (Cl. 315—84)

This application is a division of our copending application Serial No. 450,470, filed July 10, 1942, for "Mobile accounting devices."

The invention relates generally to devices adapting accounting machines for operation in vehicles and more particularly to means for illuminating tabulating equipment in trailers for military use.

An object of the invention is the provision of black-out lighting for concealing the location of the mobile accounting unit at night. The interior of the accounting trailer is provided with two sets of lights, the ordinary illuminating bulbs and a set of darkened bulbs which are used only in those intervals when the door of the trailer is opened. Hand switches are provided for use in the even of an alert to bring into operation a substitute control of lights. The alternation from use of ordinary lights to colored lights and vice versa is automatically enforced by a door switch which is situated near the door opening so as to come into operation upon the slightest movement of the door. The ordinary lights are turned off and the colored lights turned on before there is any perceptible opening seen from the outside.

Another object of the invention is the provision of a black-out control relay and wiring therefor. The wiring for the black-out relay includes a common line and an armature common to two relay contacts, said wire being connected from the armature to a hand switch for ordinary lights. The arrangement is such that the common wire is part of the circuits through the ordinary lights, the black-out lights, a door switch and the relay. A set of ordinary lights are connected to a power source through normally closed relay contacts. Upon operation of the door the relay is made effective to cause automatic transferal of current from the ordinary lights to the black-out lights.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a plan view of the interior of the trailer showing the arrangement of machines around the walls and the location of the door switch.

Fig. 2 is a wiring diagram showing the arrangement of lines, control switches and black-out relay for automatically controlling dimming of lights under control of the door operation.

In Fig. 1 is shown the arrangement of accounting machines and filing cabinets around the inner

walls of the trailer body 20. They may be identified in the order of use in a clockwise direction starting at the upper left hand corner with a card sorter 21, a filing cabinet 22, a card interpreter 23, a card grouping collator 24, a card perforating reproducer 25, a data accumulating and report printing alphabet tabulator 26, a filing cabinet 27, a card perforating duplicating punch 28, another sorter 29, and a card file cabinet 30.

10 At the one end of the trailer is a pair of outwardly swinging doors 32 and 33 giving access to the center of the trailer floor 31 which is normally clear since the machines are held close to the walls of the vehicle body. An emergency door 15 34 is provided at the opposite end of the trailer.

The various filing and card holding cabinets are secured directly to the floor of the vehicle and against the walls of the vehicle body, but the accounting machines are removably secured

20 to the floor and walls so that they may be drawn out into the center of the vehicle for changes in plugging and adjustments as well as for servicing. Each machine is provided with four shock absorbing feet which are attached to sliding runners 25 movably held in skid channels which are secured to the floor of the vehicle.

In addition to the machine carrying trailer shown in Fig. 1, another trailer is provided as an administration office wherein all information 30 and data are analyzed and transferred to the record cards which are perforated. Other vehicles carry electric current generating equipment to furnish lighting current for the trailers and motive power for the accounting machines.

35 Fig. 2 is a wiring diagram showing the electrical controls governing the lighting circuits and the motive power for the accounting machines, fans and heaters provided in the trailers. A source of power is indicated at the point PS from

40 whence lines are carried into a fuse box FB and then connected to a pair of lines 80 and 81 associated with a set of hand switches on a switchboard 82 which may be located on the inner wall of the trailer or at a remote point and connected 45 by a cable with the lighting and machine controls inside the trailer. Remote control is useful to effect immediate switch operation at an air raid detection post.

Inside the trailer a series of ordinary bright 50 overhead lights BR are provided and connected in parallel by wires 83 and 84. The circuit for these ordinary lights passes through a normally closed contact 85 of a black-out relay BK and the contact members of a hand switch LS.

55 When the hand switch LS is closed, a circuit

is established as follows: through the eight ordinary lights BR, wire 84, contacts 85, armature 87, wire 86, switch member LS and line 80. Then from the other line 81 the current continues through the other side of switch LS, over a cross-wire 88 to the light wire 83 and the overhead lights BR.

Other black-out lights BL and BL' are provided and connected selectively under control of relay BK when a black-out hand switch BS is closed. For the purpose of black-out control, a door operated switch DS is provided and a plunger 90 therein is connected with a pair of contacts 91 which are normally opened when the door is closed.

Referring to Figs. 1 and 2, it may be noted that the switch DS is suspended above the outwardly swinging door 32 by a bracket 92 fastened inside the door frame above the widely swinging side of the door. The switch is located as it is purposely in order that the contacts may be operated by the smallest displacement of the door so that the bright lights are switched off when the door swings the slightest amount toward an open position. In fact, switching takes place from the bright lights to the black-out lights before there is any perceptible crack or opening between the doors 32 and 33 when viewed from the outside.

Turning back to consideration of the circuit between the door switch and relay BK (Fig. 2), it is noted that the relay coil BK is connected with contacts 91 by a wire 94 and the other side of coil BK is connected to wire 86 which, as already noted, has connections to switch LS and line 80. Contacts 91 are connected to the other line 81 through a wire 95 connected to a black-out line wire 96 attached to one terminal of the black-out hand switch BS. The relay control circuit continues through the switch and cross-wire 88 and through the other hand switch LS to line 81.

From the foregoing description of the relay control circuit, it is evident that when contacts 91 are closed due to the opening of the trailer door, relay BK is energized, and armature 87 shifts to open contacts 85, disabling the ordinary lights, and closes contacts 97 to illuminate the dim black-out lamps BL and BL'. The black-out lighting circuit through contacts 97 and switch BS include line 80, switch LS, wire 86, armature 87, contacts 97, wire 99, switch BS, wire 98, light bulbs BL and BL', wire 96, switch BS, wire 88, switch LS and line 81. It should be noted that wire 86 is common to a number of the lighting control circuits. It forms part of the ordinary lighting circuit, the black-out lighting circuit, and the door switch and relay control circuit.

The other hand switches on switchboard 82 are provided in pairs for the control of the machine plug outlets, the heater control circuits and the exhaust fan operating motors. Switch

A, when closed, sends current through wires 100, 101 leading to machine plug outlets S1, S2, S3, S4, S5 and S6. The other hand switch A' causes connections between the power lines and wires 102, 103 leading to plug sockets S7, S8, S9. Hand switches B and B' are closed to energize one or both of the heaters H and H'. The two remaining hand switches C and C' are effective to call into operation the exhaust fans F and F'.

Wired in parallel with the plug sockets S7, S8 and S9 across the wires 102, 103, is a step illuminating black-out light SBL attached to the outside of the trailer in position to illuminate the steps leading up to the doors 32 and 33 shown in Fig. 1.

While there have been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is:

1. In an illuminating system, a series of ordinary lights, dim black-out lights, a door operated switch, a relay controlled by said switch, a power source, a hand switch for connecting said ordinary lights to said power source through normally closed contacts of said relay, a second hand switch for making said relay effective under control of said door switch, whereby opening of the door causes opening of said contacts to cut out the ordinary lights while other relay contacts in series with said dim black-out lights are closed to connect the black-out lights to the power source.

2. In an illuminating system, a power source, a door operated switch, a relay controlled by said switch and having two contacts one of which is normally closed, a set of ordinary lights connected to said power source through said normally closed contacts, and a set of dim black-out lights connected to said power source through the normally open contact of said relay, whereby operation of said door causes relay operation and automatic transferal of current from the ordinary lights to the black-out lights.

3. The combination set forth in claim 1, wherein said relay includes an armature common to both relay contacts, and a wire connected from said armature to the hand switch of the ordinary lights, said wire being common to the circuit through said ordinary lights, the circuit through said black-out lights and the circuit including said door switch and relay.
